UNITED STATES PATENT OFFICE.

JONAS C. JACOBY, OF SOUTH BETHLEHEM, PENNSYLVANIA.

STEEL CLAMP.

1,384,664.

Specification of Letters Patent. Patented July 12, 1921.

Application filed February 20, 1920. Serial No. 360,204.

To all whom it may concern:

Be it known that I, JONAS C. JACOBY, a citizen of United States, residing at South Bethlehem, in the county of Northampton and State of Pennsylvania, have invented 5 new and useful Improvements in Steel Clamps, of which the following is a specification.

This invention relates to improvements in 10 concrete forms for buildings and aims to provide a clamp for holding the walls of the form in position and may be used in the construction of building walls, chimneys, silos and the like.

15 An object of the invention is the provision of a clamp for concrete forms, which is adjustable for walls of different widths and in which the height and length of the form sections may be regulated as desired.

20 Another object is the provision of a clamp of this character, which is suspended from above and may be easily and quickly raised as the work progresses.

With the above and other objects in view, 25 the invention further includes the following novel features and details of construction, to be hereinafter more fully described, and illustrated in the accompanying drawings.

In the drawings:

30 Figure 1 is a view in elevation of a concrete form using the improved clamp.

Fig. 2 is a plan view of the same.

Fig. 3 is a section on the line 3—3 of Fig. 1.

35 Fig. 4 is an enlarged cross sectional view on the line 4—4 of Fig. 3.

Fig. 5 is a similar view on the line 5—5 of Fig. 3.

Referring to the drawings in detail like 40 characters of reference denote corresponding parts throughout the several views.

In the practical embodiment of the invention, herein shown and described, there is provided spaced parallel suspending arms 45 indicated at 10. These arms are arranged in pairs and are channel shaped in cross section, each pair being connected at their upper ends by means of a transversely arranged bar 11, which engages the arms in 50 the manner indicated at 12 so as to permit of proper adjustment. The arms are supported preferably by means of a timber 13, which may be in turn supported in any suitable manner, such as by jacks and cribbing 55 (not shown).

The supporting arms are channeled in

cross sectional shape and each pair are so spaced as to receive in their channels the ends of timbers 14, which form the side walls of the mold and between which the material is placed in the formation of a wall. These timbers are separately placed within the channels of the supporting arms and the walls formed thereby may be raised to any desired height by the insertion of 60 the proper number of timbers. For the purpose of adding length to the side walls of the mold, the supporting arms 10 have secured thereto a channeled member 15, the latter being arranged with its channel extending in a direction opposite from the channel of the supporting arm 10 so as to provide for the reception of the ends of additional timbers 14. This channeled member 15 may be shown shorter in length 65 than the supporting arms 10 and may be secured to the said arms through the medium of suitable bolts or rivets 16. It is of course obvious that instead of securing together oppositely extending channel members, an H beam may be substituted for the arms 10.

In order to provide for proper adjustment of the arms of each pair, each arm has pivotally connected thereto upper and lower 70 links 17, the latter in turn having pivotally connected thereto nuts 18, the latter serving to pivotally connect the links of opposite supporting arms. Operating within the nut 18 is an adjusting rod 19, the ends of 75 which are oppositely threaded, so that by rotating this rod the arms may be drawn together or separated as desired. This may be accomplished by the insertion of a suitable tool in the openings 20 provided for 80 that purpose.

The invention is susceptible of various 85 changes in its form, proportions and minor details of construction, and the right is reserved to make such changes as properly 90 fall within the scope of the appended claims.

For example, the adjusting screw may be removed from the supporting arms and the latter connected by the insertion of a solid steel bar when the invention is used in extra 95 heavy walls.

Having described the invention what is claimed is:—

1. A concrete form comprising suspending 100 U-shaped arms arranged in pairs, sectional side walls detachably secured thereto, links pivotally connected to the opposing 110

sides of the said arms, a nut pivotally connecting the links and a threaded rod engageable with the nuts to provide relative adjustment of the arms.

5 2. A concrete form comprising suspending U-shaped arms arranged in pairs, sectional side walls detachably secured thereto,

U-shaped members secured to said U-shaped arms, links pivotally connected to said arms, a nut pivotally connecting said links and a threaded rod engageable with the nut to provide relative adjustment of said arms.

In testimony whereof I affix my signature.

JONAS C. JACOBY.
